UNITED STATES PATENT OFFICE.

BENJAMIN H. ALVEY, OF LOUISVILLE, KENTUCKY, ASSIGNOR OF ONE-HALF
TO CHARLES H. ROBERTS, OF WASHINGTON, INDIANA.

DESIGN FOR A STOPPER OR NOZZLE.

SPECIFICATION forming part of Design No. 31,128, dated July 4, 1899.

Application filed June 10, 1899. Serial No. 720,095. Term of patent 14 years.

To all whom it may concern:

Be it known that I, BENJAMIN H. ALVEY, a citizen of the United States, residing at Louisville, in the county of Jefferson and State of Kentucky, have invented and produced a new and original Design for a Stopper or Nozzle; and I do hereby declare the following to be a full, clear, and exact description of the invention, such as will enable others skilled in the art to which it appertains to make and use the same.

This invention relates to valved closures for bottles and like containing-receptacles, the object being to provide a stopper or nozzle of unique and novel design, which is shown in the accompanying drawings, in which—

Figure 1 is a perspective view of the device. Fig. 2 is a front view. Fig. 3 is a top plan view.

The vital feature of the invention is a stopper and a nozzle of approximately S form,

having its members straight and parallel and one in vertical alinement with the stopper.

The stopper 1 is of frusto-conical form and is disposed with the smaller base lowermost and has an outer bead or extension 2 at its upper end. The nozzle 3 is of S or goose-neck form, the end portions 4 and 5 being straight and in parallel relation and the intermediate portion 5' being of ogee form. A bead 6 is formed at the extremity of the nozzle or part 4.

Having thus described the invention, what is claimed as new is—

The design for a stopper and nozzle, substantially as herein shown and described.

In testimony whereof I affix my signature in presence of two witnesses.

BENJAMIN H. ALVEY. [L. S.]
